March 12, 1940, Serial No. 323,529. In Great
Britain May 19, 1939

11 Claims. (Cl. 210—55)

This application stands in the place of applicant's abandoned application Serial No. 264,262 filed March 26, 1939.

This invention relates to thickeners, clarifiers, or similar sedimentation apparatus and especially to those embodying a cornered non-circular basin or tank and an associated sediment-impelling and transferring assemblage that is horizontally-turnable about a vertically-extending axis. Such apparatus is known that comprehends, (1) a main raking mechanism movable about a vertically-extending axis in closed circular paths over a circular section of the tank bottom and provided for transferring sedimented material from diverse portions of the circular bottom section of the tank to a sediment discharge means leading from a lower interior portion of the tank, and (2), a corner-exploring and cleaning mechanism disposed for successively operating over or within the outlying angular or corner sections that are proximate and extend beyond the circular section of the tank bottom, for example, exploring mechanism disposed for successively engaging sedimented material in the several corner sections and for transferring the sedimented material engaged thereby from the diverse portions of the successive corner sections to the central floor section from whence it is ultimately transferred to the sediment discharge by the functioning of the raking mechanism.

One object of this invention is to provide a simple and positively acting sediment conveying corner-exploring device cooperatively associated with a carrier which is rotatable about a vertical axis and in which a corner-exploring element performs positively controlled successive outward and inward movements in timed coordination with the rotation of said carrier.

According to the present invention this object is attained by imparting to the exploring element a crank-controlled movement, the crank arm performing a number of complete revolutions or cycles during each complete revolution of the carrier, which is equal to the number of corners of the polygonal settling area served by the mechanism.

According to one feature, gearing is cooperatively associated with the crank and with drive means for the carrier, so that the number of crank revolutions per one revolution of the carrier, is equal to the number of corners of the polygonal settling area.

In one embodiment the carrier is rotatively supported on a pier and the drive means comprise a force-resisting member or gear which is

fixed to the pier and consequently, with respect to the vertical rotary axis of the carrier. Power transmission means are associated with the carrier on the one hand and with the fixed gear on the other hand for positively turning the carrier, while the exploring element has imparted thereto positively controlled movement through properly geared transmission means operatively connecting the drive means with the exploring element.

As illustrative of the manner in which the invention hereof may be structurally embodied in an apparatus or unit of the class referred to, reference is made to the accompanying drawings constituting a part of this specification.

In said drawings:

Fig. 1 is a plan view, partially broken away, of one embodiment of the invention;

Fig. 2 is a partial vertical sectional view of the embodiment illustrated by Fig. 1;

Fig. 3 is a perspective view of an end portion of a main raking arm or main sediment-raking member employed in the embodiment of Fig. 1 and Fig. 2;

Fig. 4 is a view diagrammatically illustrating various positions of a corner-exploring element and of a novel actuating mechanism therefor when functioning within a relatively square tank or as otherwise expressed when operating over the successive cornered floor portion of the tank bottom;

Fig. 5 is a view diagrammatically illustrating the various positions of a corner-exploring element and of the actuating mechanism therefor when functioning over and within the successive apex or cornered sections of an equilateral and equiangular floor area or polygonal operating space typified by one which is hexagonal;

Fig. 6 is a view taken upon the line 6—6 in Figs. 1 and 2, and showing the more detailed and amplified structure of the rotary mounting and drive for the main rotary carrier of the mechanism;

Fig. 7 is an enlarged detailed sectional view of the crank arms controlling the movement of the corner exploring element, as taken on line 7—7 in Fig. 2;

Fig. 8 is a further enlarged and further detailed sectional view as taken on line 8—8 in Fig. 7 showing a pivot connection between a crank arm and the corner exploring element;

Figs. 9 and 10 are details similar to Figs. 7 and 8 respectively, but they represent enlarged details of the sediment conveying member and their controlling crank arms in an arrangement and

position taken from Fig. 4, Fig. 10 being an enlarged detailed section taken along the line 10—10 in Fig. 9.

Reference will now be made to the drawings in detail.

The sedimentation unit shown in plan in Fig. 1, of which certain sections of the tank or basin have been broken away, includes a cornered non-circular settling tank or sedimentation basin 11 and a horizontally-turnable sediment-raking assemblage 12. The invention hereof is particularly useful in connection with tanks or basins of which the relatively flat or straight inner surfaces 13 of the marginal wall 14 are disposed substantially after the order of the faces of an equilateral and equiangular polyhedron, or in which the floor area to be raked is in the form of an equilateral and equiangular polygon which may be in the form of a triangle, square, pentagon, hexagon, septagon or octagon. In general, however, when employed in sedimentation units it will be in connection with square, hexagonal or octagonal tanks or basins or in tanks or basins having square, hexagonal or octagonal floor areas to be raked. The tank or basin 11 of Figs. 1 and 2 is of the form which is usually referred to as a square tank. This statement applies even though there is a fillet or corner filling section 15 at each apex or cornered section of the tank wall. In this connection it should be noted that each apex or cornered section of any other equiangular and equilateral polygonal form or area with which the invention hereof is employed has a fillet or curved corner filling section 15. Moreover, for each fillet the arc shaped face or curved marginal line thereof merges into the relatively flat face portions or relatively straight defining lines adjacent thereto but upon opposite sides of the particular fillet.

In the embodiment of Figs. 1 and 2 the tank bottom has a central circular section that is defined and located, for example, within the circular lines 2, 4, 5, 6, 6a, etc.

This circular floor section slopes downwardly and inwardly toward a central sump or depressed sediment-discharge 16, located at or adjacent a fixed central pier or stationary supporting structure 17 rising from the bottom of the tank or basin. Proximate and extending outwardly from the circular central floor section there are located the apex or cornered floor sections delineated, for example, by lines such as 4, 2, 7, 8, and 9. The surface of each of the cornered floor sections is horizontal or substantially so since that is the preferred form of construction where there is employed a corner-exploring and raking element that is mounted and actuated according to the invention thereof.

A member providing a stationary bearing 18 is carried by or embodied in the pier or stationary structure 17. A fixed torque absorbing or stationary force-resisting member 19 which may be in the form of a gear is fixed to the pier or stationary structure 17. The horizontally-turnable raking assemblage 12 derives its support from the stationary bearing 18 and the fixed torque-absorbing gear or stationary torque-resisting member 19 constitutes part of a motor-actuated mechanism 20 that is employed for turning the raking assemblage about a vertically-extending main axis which coincides with the geometrical axis of the stationary bearing and the central pier. When a fixed gear as 19 is employed as the torque-resisting and absorbing member, then a motivated gear type of element

is employed which is operatively associated therewith. By way of example the motivated element may be a main driving worm or strong endless screw 21 that is carried on or functionally embodied in the raking assemblage as a part thereof. This motivated worm or endless screw meshes with the teeth of the fixed gear whereby as the worm or screw turns it bodily moves about the fixed gear thus imparting the horizontal turning movement to the raking assemblage 12.

In the construction shown the main worm or endless screw 21 is on and driven through the medium of a horizontal shaft 22 that is part of the motivated mechanism 20 that has motor 23 as the actuating means therefor and speed reducing and power transmitting gearing 24 for driving the shaft 22 from the rotor of the motor.

As to the horizontally-turnable raking assembly 12, this in the embodiment shown comprises a carrier 30 having a movable bearing 31 turnably mounted on the stationary supporting bearing 18. This turnable bearing 31 thus serves as the medium by which the carrier and all parts thereof or supported therefrom derive ultimate support from the stationary structure and at the same time provides an arrangement of parts whereby the raking assemblage can turn about the vertically-extending central axis as and when the motor operates.

The horizontally-turnable carrier 30 embodies or provides a depending central body or body portion 30 and a radial carrier arm 32 extending therefrom outwardly toward the marginal wall of the tank. The carrier arm is of such shape and length as to permit an unobstructed full turning movement in closed horizontal paths about the carrier axis. The corner-exploring element which has heretofore been referred to is designated by the reference character 33. It is ski-shaped and has a curved toe portion 34 and a relatively straight body portion 35. It is supported from the outer end of the carrier arm 32 through the medium of small worm gears 36—36 that rest upon bearing members provided on the arm, vertical shafts 37—37 secured to, carried by and depending from the small worm gears 36—36 and turnably mounted in bearings provided within the projecting portions or depending members 38—38 of the carrier arm, cranks or crank elements 39—39 secured to and extending from the lower ends of the vertical shafts and which function much after the order of horizontally-swingable parallel links, and pivotal type of connecting means or crank pins 40—40 through the medium of which the body portion 35 of the corner-exploring element 33 is pivotally-mounted below and is supported in a depending position from the outer or swinging ends of the cranks or links 39.

The shaft 22 to which this main driving worm 21 is secured extends along the carrier arm 32 and is mounted therefrom through the medium of bearings provided in sets of lateral extensions 25—25, 26—26 and 27—27. The horizontal shaft 22 is mounted so that it can turn in said bearings and is secured against longitudinal movement in said bearings; in other words, so that there is permitted at the most only a limited amount of longitudinal movement of or horizontal play for the shaft. The shaft 22 has mounted thereupon and so as to be driven thereby two small worms or endless screws 41—41 which mesh with the corresponding small worm gears 36—36, sometimes referred to as crank gears. From what has preceded, it will be mani-

fest that as the shaft 22 turns it imparts uniform turning movements to the worm gears 36-36, the shafts 37-37 and the cranks or crank elements 39-39 and consequent successive in and out horizontal movements to the corner-exploring element or ski-shaped member 33.

The shafts 37-37 are disposed a sufficient horizontal distance apart to permit a full turning movement of each crank or link 39 carried thereby about the vertical axis corresponding thereto without experiencing any interference with the other crank or shaft carrying the same. The vertical axes about which the shafts 37-37 and the cranks or crank elements 39-39 turn are sometimes referred to herein as secondary vertical axes that are horizontally-spaced from the main axis and also from each other. This means that in the construction shown one vertical shaft 37 is outwardly disposed from the main vertical axis a greater distance than the other shaft. In short, the horizontal distance between said crank shafts 37-37 is somewhat greater than the radial length of either of said cranks. The cranks are the same length. In the construction shown the vertical shafts 37 are disposed approximately along the same radial line.

The shafts 37-37 being vertical and the pivotal connections 40-40 at the outer ends of the cranks being at the same elevation, it will be manifest that the corner-exploring element will move in horizontal paths as the cranks turn.

The gearing which embodies the worms and worm gears mentioned is proportioned and timed so that for each complete turning movement of the carrier and carrier arms about the main vertical axis there is completed a number of turns of each of the small worm gears 36-36, or what is the same thing a number of complete turns of each of the cranks 39-39 relative to the carrier arms, equal to the number of the cornered or apex sections of the particular polygonal area or space over or in which the raking assemblage operates. In the instance of the square tank of Fig. 1 the cranks move the corner-exploring element through four complete but successive epicycloidal movements. During each complete epicycloidal movement the corner-exploring member moves from an innermost retracted position, to wit, from the central portion of a flat inner face or straight marginal line first progressively outwardly until it reaches full extended position within and at the apex portion of the cornered section and thereafter progressively inwardly until it reaches its subsequent innermost retracted position by the time the corner-exploring element has arrived opposite the central portion of the succeeding flat face or straight marginal line.

In designing a corner-exploring mechanism with a corner-exploring element so that the outermost end thereof will have successive relatively long straight line movements along each of the straight lines or flat face portions and successive relatively short movements along the relatively short curved or approximately arcuate region at the fillet or filled in corner section between adjacent flat surface or straight line section of the polygonal surface or area, it becomes necessary to adopt a proper length for the cranks by which the corner-exploring element is carried.

This length may be geometrically determined as follows:

Take the short radius of the polygonal figure, or as otherwise expressed, the radius of the circle to which the flat faces or straight sides of the polygonal figure are tangent and extend the

straight tangent lines to the point 10 where they intersect, thus providing the apex or point 10. Then extend the radial line 0-3 from the point 3 of Fig. 1 to point 10. Such extension of the radial line is from the point 3 on the circle to the point 10 which is the apex 10. Divide the line 3-10 into three equal parts; one of these parts is 8-10. The corner or apex portion between the points 8 and 10 can be filled in by a fillet. The remaining portion or length as indicated by the line 3-8 indicates the total length of throw which the cranks should have for imparting to the corner-exploring element the afore-described successive epicycloidal movements. The approximate length of each of the cranks should therefore be one-third of the length of the line 3-10. The geometrical system just described can be employed for determining the length, or approximate length of crank for operating a corner-exploring element within or over any equilateral equiangular polygonal space or area. It also results in a relatively straight line movement for the outer end of the corner-exploring element 33 except for the movement along the relatively short curved fillet or arc-shaped portion.

The geometrical system of determining the operative length of the cranks 39 has been described in connection with a square or four-sided tank. The same scheme, however, can be employed to illustrate a trigonometrical method of determining the crank length.

In this connection with the trigonometrical method it will be noted:

(a) That the tank has N number of cornered sections or apex portions and in the case of a square tank N is 4;

(b) That the angle 1-0-10 (see Fig. 1) is equal to—

$$\frac{180}{\text{number of cornered sections}} = \frac{180}{N}$$

and thus where N is 4 the angle 1-0-10 is 45 degrees;

(c) That the line 0-10 (see Fig. 1) is the secant of a 45 degree angle of a circle of which the radius 0-1 is indicated by R; and

(d) That the length in inches of each crank 39 is equal to product of R in inches multiplied by the value of the trigonometrical secant of a 45 degree angle as taken from the table of trigonometrical functions, from which product then is thereafter subtracted the number of inches of R, and which remaining difference is then divided by 3.

A general formula for any type of equilateral equiangular polygonal figure is trigonometrically expressed as follows:

$$X = \frac{R}{3} \left\{ \secant of angle \frac{180}{N} - R \right\}$$

In said formula:

60 R=the "short" radius in inches of the polygonal figure, or as otherwise expressed, is the radius of a circle inscribed in the polygonal figure and tangent to the straight sides—or faces of the polygonal figure;

65 X=the length in inches of one-half of the crank throw or radial length of crank that actuates the corner-exploring element; and N=number of straight sides of the equiangular polygonal figure or as otherwise expressed, the number of the cornered or apex portion of such figure.

For polygonal figures having 3, 4, 6 or 8 sides said equation for determining the length of X becomes respectively as follows and furthermore,

when R is taken as unity, then the equation assumes a still more simple form as is clear from the formulas expressed below.

When determining crank lengths for use in connection with:

Triangular polygonal figures then—

$$X = \frac{R}{3} \{ \secant \text{ angle } 60^\circ - R \} =$$

$$\frac{1}{3}(2-1) = \frac{1}{3} \text{ the unit or } \frac{R}{3} \quad 10$$

Square polygonal figures then—

$$X = \frac{R}{3} \{ \secant \text{ angle } 45^\circ - R \} =$$

$$\frac{1}{3}(1.414-1) = .138 \text{ of the unit or } .138R \quad 15$$

Hexagonal polygonal figures then—

$$X = \frac{R}{3} \{ \secant \text{ angle } 30^\circ - R \} =$$

$$\frac{1}{3}(1.547-1) = .051 \text{ the unit or } .051R \quad 20$$

Octagonal polygonal figures then—

$$X = \frac{R}{3} \{ \secant \text{ angle } 22\frac{1}{2}^\circ - R \} =$$

$$\frac{1}{3}(1.0824-1) = .027 \text{ the unit length or } .027R \quad 25$$

For the length of each of the cranks 39—39 it is in order to adopt substantially the length deduced by the general trigonometric formulae expressed. Nevertheless, this may be departed therefrom or modified to a limited extent and still obtain the substantially desired movements of the outermost end of the corner-exploring element along polygonal paths which have relatively straight sides included in equilateral paths of which the apex portion is modified so to speak by the short curved or arcuate sections heretofore referred to. In this connection, it will be noted that lengthening of the crank results in causing the outermost limit of travel of the corner-exploring element to be further outwardly from the main vertical axis particularly for the movements in and adjacent the apex portion of the polygonal surface or area served thereby, and conversely shortening of the cranks results in lessening of the outermost limits of movement for the exploring element, particularly in the general region of the apex sections of the polygon spaces or areas.

It will be understood from the foregoing that the number of revolutions of the cranks 39 per one revolution of the carrier arm 32 must be equal to the number of corners of the polygonal settling area to be served by the mechanism. Consequently, the ratio of the worm gear 19 to each of the worm gears 36 must be 4:1, provided both the worm 21 and the worms 41 are of the single threaded type.

While the invention hereof primarily revolves about and essentially relates to the corner-exploring mechanism, already fully described, nevertheless, a specific and particular application thereof is its employment in and embodiment as part of a sediment-raking assemblage for raking and collecting sediment from substantially all of the various and diverse sections of a tank bottom or area over which the assemblage horizontally turns and for transferring the raking sediment to a sediment discharge leading from the tank. The sediment raking assemblage therefore embodies the corner-exploring mechanism which engages sediment within and transfers sediment from the cornered sections or areas served thereby to a circular central section and it embodies a main raking

mechanism which operates in horizontal circular paths over the central section and which functions to engage sediment that is on or within the central circular area toward and to the sediment discharge leading from the tank.

The main raking mechanism in the embodiment of Fig. 1 is provided on the carrier and includes a radially-extending rake arm 45 having or embodying bladed raking elements 46, 47, 48, etc. The rake arm 45 is supported from the depending body portion 50 of the carrier 30. The outer end portion of the rake arm is shown in perspective in Fig. 3. It is formed of structural shapes such as rolled angles 51, 52, 53 and 54 providing longitudinals that are connected into a relatively rigid structural formation by upper transverse tie members 55, 56, etc., vertical tie members 57, 58, etc., diagonal brace elements such as 59, 60, 61, 62, etc., and also by the raking blades 46, 47, 48, etc., previously referred to.

In order to complete a light but rigid shallow end construction for the rake arms the outer ends of the upper longitudinals 51 and 52 are bent down toward and connected to the corresponding lower longitudinals 53 and 54. An inspection of Fig. 3 will make it clear that the rake arm 45 is a skeleton type of box-like formation that is shallow, wide, relatively strong and rigid and of a character which will impart at the most only a slight local disturbance within the lower portion of the body of relatively quiescent liquid within which it operates. An inspection of Fig. 1 will make it clear that this main raking mechanism functions over and serves to collect and transfer sediment over and within the circular areas bounded by the circles 1, 2, 3, 4, 5, etc., to wit, over an area bounded by a circle that is tangent within the straight side portion of the equilateral equiangular polygonal area or spaces served by the sediment raking assemblage as a whole. This main raking mechanism serves or functions to convey to discharge sedimented material that has been passed to said central circular space or area by the corner-exploring mechanism, and also sediment originally deposited in or on said central circular space or area.

According to Fig. 1 and also according to diagrammatic Figs. 4 and 5, the main carrier 30 or the radial carrier arm 32 thereof moves in clockwise direction, as is indicated by the large arrows A and the cranks 39, which are carried from and move with but in respect to the main carrier or carrier arm, turn in counterclockwise directions as is indicated by the arrows B.

In the construction shown in Fig. 1 the body portion 35 of the ski-shaped corner-exploring member 33 is connected to the swinging or outer ends of the cranks in a manner whereby it is located immediately or directly below the pivotal connections to the cranks.

It can be said that one of the gear actuated cranks or crank arms 39 would suffice to impart to the corner-exploring element 33 the desired succession of inward and outward movements through the crank pin or pivotal connection or pivot portion 40, and that the other crank arm 39 and pivotal connection 40 in its function be considered as a guide means for the exploring element 33, both the first mentioned crank arm 39 and the guide means then being coactive and effective to determine the bodily movements of the exploring element 33 along a predetermined path. These guide means operatively connect a portion of the main carrier 30 (which portion is horizontally spaced from the locality of the

mounting of the associated crank arm 39 on the main carrier), with a portion of the exploring element 33 (which latter portion is horizontally spaced from the locality of said crank pin 40). In further definition of these guide means it can be said that they comprise a guiding member (namely an arm 39) on the main carrier 30 and a corresponding guided portion provided on the exploring element 33, and a pivot portion 40 operatively interconnecting the guiding member and the guided portion.

The detailed sectional views in Figs. 7 and 8 show more clearly the pivotal connection 40 interconnecting the crank arms 39 and the corner-exploring element 33. The pivotal connection 40 in particular is shown in Fig. 8 to comprise a pivot portion 40^a fixed as by welding to the corner-exploring element 33, and rotatable in a bushing 40^b provided in the swinging outer end of the crank arm 39, and held in place by a collar 40^c and cotter pin 40^d. It will be understood that as a mere reversal of parts, the pivotal connection between the crank arms 39 and the corner-exploring element 33, may on the other hand comprise a pivot portion or crank pin that is fixed to the crank arm 39 and rotatable with respect to the corner-exploring element 33.

In the construction shown in Figs. 4 and 5 the ski-shaped corner-exploring element is connected to the swinging or free outer ends of the cranks so as to have a general outward and forward inclination or slope with respect to a line or vertical plane passing through the outer ends of the cranks. This is otherwise definable as follows:

The one of the two cranks 39 which lies nearer to the rotary center O of the carrier arm 32, is herein called the inlying crank 39, while the other is herein called the outlying crank 39.

The body 35 of the ski-shaped element 33 is connected to the outer or swinging ends of the cranks 39 in such a manner that when the crank arms are in trailing position as indicated at P in Fig. 4 that portion of the ski-body which is nearest the swinging or outer end of the inlying crank 39 trails or is behind the swinging or outer end of the inlying crank because that outer end is pivotally connected with a forward projection 63 (see Fig. 4) provided on the ski body and that portion of the ski body which is nearest the free end of the outlying crank 39 precedes or lies ahead of the swinging or outer end of the outlying crank because that swinging end is pivotally connected with a rearward projection 64 (see Fig. 4) provided on the body. In considering the foregoing remarks one should bear in mind that the general forward direction is indicated by the arrow A. This mode of connecting the ski-shaped corner-exploring element to the crank arm is illustrative of a form that has advantageous features that are preferably used in certain installations.

The area or region served by the corner-exploring mechanism embodying the invention hereof may be referred to as a modified equilateral equiangular polygonal figure because of the modifications imparted thereto by the fillets or arc-shaped formations provided at or in the apex portions thereof. An equilateral equiangular polygonal area or region of substantially the same size which does not have fillets or arc-shaped formations at the apex thereof is herein referred to as a true geometrical equilateral equiangular polygon corresponding to the modified equilateral equiangular polygonal figure. In the equivalent true geometrical and modified polygonal figures any radius extending from the center of a figure

and which is normal or perpendicular to any side thereof is referred to as the short radius, and the length of this short radius is the same for both the true and modified polygonal figures. The distance from the center of the true geometrical polygonal figure to an apex thereof is referred to as the long radius. The length of this long radius of the true geometrical figure is the one which should be employed in determining the length of a crank 39 according to the method hereafter referred to. This long radius is in fact the length of the secant of the angle bounded by adjacent long and short radii. The length of each crank 39 for operating in any polygonal figure may be expressed as one-third of the differential between the long and short radii of the true geometrical equilateral equiangular polygonal figure, which differential is represented by the distance or line 3-10 (see Fig. 1). Each of the several fillets or arc-shaped sections of the modified figure occupies an area which comprehends as a marginal point thereof, a point which is inwardly located with respect to an apex of the true geometrical figure a distance substantially equal, or approximately so, to one-third of the difference between the long and short radii of the true geometrical figure.

In connection with the sedimentation unit or apparatus described, it is in order to note that any suitable means for supplying liquid to the tank or basin may be employed, as for example, a central feed which may involve a delivery of liquid into the central regions of the tank. Such feed may be through the central pier 17 which may be hollow for providing an upflow discharge leg as 65 of an inverted siphon type of influent supply means. The unit also embodies any suitable outflow means which by way of illustration may comprehend a marginal overflow weir 66 provided at or by the boundary walls of the tank. The features of construction just referred to relate to feed supply means and supernatant liquid withdrawal means all of which are old and well known in the sedimentation art. As is usual in sedimentation units or clarification apparatus of the type referred to the overflow weir determines the normal level of the liquid within the tank. In the construction illustrated the main portion of the carrier arm 32 and also supporting bearing surface provided by stationary bearing 18 are located at elevations above that of the normal level of the liquid within the tank.

I claim:

1. A sediment impelling and transfer mechanism for operating within a space defined by cornered sedimentation area which in plan is substantially equilateral, equiangular and polygonal, said mechanism comprising in combination a supporting bearing member providing a vertically-extending axial center, a movable main carrier mounted on said supporting bearing member for horizontal rotation about said axial center, motivated means for turning said movable main carrier in a closed path about said axis, sediment-raking elements extending downwardly from and movable with said carrier for operating over a circular portion of the sedimentation area corresponding to said closed path, horizontally-turnable crank elements supported from said main carrier, a corner-exploring sediment conveying element, a crank pin connection between said exploring element and the outer end of each of said crank elements and said conveying element disposed for operating over cornered sections of the sedimentation area that are proximate to but

that extend beyond the circular sedimentation area served by the depending raking elements, and gearing operatively associated with said motivated means and said turnable crank elements, said gearing providing a ratio whereby each complete turning movement of the main carrier produces a number of complete revolutions of each crank element, equal to the number of the corners of the sedimentation area, the movements of said crank elements being timed through said gearing with each other and with the movement of the main carrier in a manner to cause said corner exploring element to move into and out of said cornered sections so as to convey sediment therefrom to said circular sedimentation area, as said main carrier turns.

2. A mechanism for operating over a polygonal settling area having cornered portions and comprising in operative combination and arrangement a supporting bearing member, a movable main carrier mounted on said supporting bearing member and rotatable about a vertically-extending main axis determined by said supporting bearing member and thus turnable in a horizontally-extending closed path about said axis, motivated mechanism for turning said main carrier about said main axis, a set of crank elements the inner end portions of which are turnably supported from the main carrier so as to move in horizontal paths each about a vertically-extending secondary axis horizontally-spaced from and substantially parallel to the main axis and which secondary axes are spaced from each other a horizontal distance greater than the horizontal length of the crank elements whereby each crank element can make a complete turn without interference with the other, a corner-exploring sediment conveying element, a crank pin connection between said exploring element and the outer end of each of said crank elements, and gearing operatively associated with the motivated mechanism and with the crank elements, said gearing providing a ratio whereby each complete turning movement of the main carrier produces a number of complete revolutions of each crank element, equal to the number of corners of the sedimentation area, the movements of said crank elements being timed through said gearing with each other and with the movement of the main carrier in a manner to cause the said corner exploring element to move into and out of said cornered sections so as to convey sediment therefrom, as said main carrier turns.

3. A sediment raking mechanism comprising the features of construction as defined in and by claim 2, wherein the main carrier includes a rake arm having fixed blades for operating over a circular area within the bounds of the polygonal area over which the mechanism operates, which circular area is substantially tangentially associated with the sides of the polygon of said polygonal area.

4. A mechanism as defined in and by claim 2, wherein the gearing is designed, when the main carrier turns in a clockwise direction about the main axis, to cause each crank element to turn in counter-clockwise direction about the secondary axis corresponding thereto.

5. A mechanism as defined in and by claim 2, wherein the corner-exploring element in plan is in the form of a ski having a straight main portion and a curved outer end portion, and disposed with the curved end portion extending forwardly and outwardly, the forward direction being determined by forward clockwise movement of the

main carrier, and in which the crank pin connections are disposed at points spaced along said main portion of the ski.

6. A mechanism as defined in and by claim 2 for operating in a polygonally shaped tank of which the inner faces of the marginal wall of the tank define in plan an equilateral equiangular sedimentation area having rounded corners by virtue of which it represents a round-cornered equilateral equiangular sedimentation area as distinguished from an otherwise corresponding but relatively sharp-cornered equilateral equiangular polygonal figure the corners of which are represented by the angle of intersection of the lines representing the sides of the polygon, and in which mechanism the effective length of each crank arm of the crank elements is approximately equal to one-third of the differential in the length of the radii of the inscribed and the circumscribed circles of said relatively sharp-cornered equilateral equiangular polygonal figure.

7. An exploring sediment conveying assemblage for a sedimentation tank or basin providing a polygonal settling area which assemblage when 25 in operating position with respect to the tank comprises in operative combination and arrangement a supporting bearing fixed against turning movement with respect to the tank, a carrier turnably mounted on said bearing for movement about a vertical main axis, a force-resisting gear element fixed against turning movement with respect to said supporting bearing, motivated mechanism comprising power transmission gearing operatively associated with said carrier on the one 30 hand and said force-resisting gear element on the other for positively turning said carrier about said main axis, a sediment conveying exploring element adapted for successive inward and outward movements with respect to said main axis for conveying sediment from the corners of said settling area, actuating means for said exploring element, comprising a crank element mounted on said carrier and turnable about a secondary axis horizontally-spaced from the main axis and having a crank pin co-operatively associated with the exploring element so that the continuous turning of said crank element about its secondary axis imparts said successive movements to the exploring element, guide means operatively connecting a portion of said carrier, which portion is horizontally spaced from the locality of the mounting of said crank element on said carrier, with a portion of said exploring element, which latter portion is horizontally spaced from the locality of said crank pin, said guide means comprising a guiding member on said carrier, a guided portion on said exploring element and cooperatively associated with said guiding member in said successive inward and outward movements of the exploring element, an operative connection including a pivot portion between the guiding member and the guided portion, whereby the exploring element is movable horizontally about said pivot portion while progressing bodily in said successive inward and outward movements as said crank element rotates, and gearing being cooperatively associated with said crank element and with said motivated mechanism, and designed to provide a ratio whereby each complete turning movement 40 of said carrier produces a number of complete revolutions of said crank element, equal to the number of the corners of the sedimentation area, the movement of said crank element being timed through said gearing with the movement of said carrier in a manner to realize said successive in-

ward and outward movements of the exploring element, whereby sediment is conveyed from the corners of the settling area as said carrier turns.

8. An exploring sediment conveying assemblage for a sedimentation tank or basin providing a polygonal settling area and having an equilateral equiangular polygonally shaped settling area to be served thereby, said area having rounded corners by virtue of which it represents a modified polygon, which assemblage when in operative position in the tank comprises in operative combination and arrangement a stationary supporting bearing determining a vertical main axis, a carrier turnably mounted on said supporting bearing for horizontal movement about said axis, a force-resisting member fixedly positioned against turning movement with respect to said stationary supporting bearing, motivated power transmission means associated with said carrier on the one hand and said stationary force-resisting member on the other hand for positively turning said carrier about said axis, a corner-exploring element mounted for having imparted thereto successive outward and inward predetermined bodily movements with respect to said main axis, crank elements mounted on said carrier and turnable about vertical secondary axes that are horizontally-spaced from the main axis and having crank pins operatively engaging the corner-exploring element so that during the repetitive turning thereof there is successively realized for the corner-exploring element with respect to the main axis an outward movement to a full extended position and an inward movement to an innermost retracted position, and gearing associated with the aforementioned motivated means and with the crank elements for continuously turning the latter while the carrier is turning about the main axis and at a constant ratio with respect to the turning movement of the carrier about the main axis, said ratio being such that each complete turning movement of the carrier is accompanied by a number of complete revolutions of said crank elements, equal to the number of corners of said polygon, the movements of said crank elements being timed through said gearing with each other and with the movement of said carrier in a manner to cause said exploring element to move into and out of said corners, so as to convey sediment therefrom, as the carrier turns.

9. In a sediment conveying mechanism for col-

lecting sediment over and from a cornered settling area, and having a carrier rotatable about a vertical main axis and over a circular portion of said settling area, and also having drive means for rotating the carrier, a corner exploring device operatively mounted upon said carrier for collecting sediment from the corner portions of the settling area into the circular portion thereof, and comprising a corner exploring element, an arm mounted on said carrier, to turn horizontally about a vertical axis, a pivotal connection to mount the exploring element on said arm, to turn about a vertical axis, guide means operatively connecting a portion of said carrier, which portion is horizontally spaced from the locality of the mounting of said arm on said carrier, with a portion of said exploring element, which latter portion is horizontally spaced from the locality of said pivotal connection, said guide means comprising a guiding member on said carrier, a guided portion on said exploring element and cooperatively associated with said guiding member for causing successive inward and outward movements of the exploring element with respect to the vertical main axis of the carrier, an operative connection including a pivot portion between the guiding member and the guided portion of the exploring element, whereby the exploring element is movable horizontally about said pivot portion while progressing bodily in said successive inward and outward movements as said arm rotates, and control means comprising driven means connected to the arm, motion transmitting means driven by said carrier drive means for driving said driven means, for continuously turning said arm a number of complete revolutions relative to the carrier for each revolution of the carrier, whereby said exploring element is caused to move along a pathway defining a cornered area from which sediment is thereby removed as the carrier rotates.

10. Apparatus according to claim 9, in which said guiding means comprise an arm one end of which is pivotally mounted on said carrier, and upon the other end of which is pivotally mounted said exploring member.

11. Apparatus according to claim 9, in which the motion transmitting means comprise gear means effective between said carrier drive means and said driven means connected to the arm.
